UNITED STATES PATENT OFFICE

167,914

NURSING BOTTLE

Alman J. Taranton, Riverside, Conn.

Application October 23, 1951, Serial No. 17,071

Term of patent 14 years

(Cl. D83—8)

To all whom it may concern:

Be it known that I, Alman J. Taranton, a citizen of the United States, and a resident of Riverside, Fairfield County, Connecticut, have invented a new, original, and ornamental Design for a Nursing Bottle, of which the following is a specification, reference being had to the accompanying drawing, forming a part thereof:

Fig. 1 is a perspective view of a nursing bottle showing my new design; Fig. 2 is a front elevation; Fig. 3 is a top view and Fig. 4 is a bottom view thereof.

I claim:

The ornamental design for a nursing bottle, as shown.

ALMAN J. TARANTON.
